UNITED STATES PATENT OFFICE.

LLOYD GROFF COPEMAN, OF FLINT, MICHIGAN.

ELECTRIC SWITCH.

1,069,531.

Specification of Letters Patent.

Patented Aug. 5, 1913.

Application filed December 23, 1911. Serial No. 667,529.

To all whom it may concern:

Be it known that I, LLOYD GROFF COPEMAN, a citizen of the United States of America, residing at Flint, in the county of Genesee and State of Michigan, have invented certain new and useful Improvements in Electric Switches, of which the following is a specification, reference being had therein to the accompanying drawings.

10 The invention relates to electric switches being more particularly designed for use in connection with automatically operating switch closing mechanism.

It is the object of the invention to obtain 15 a simple construction of snap switch which may be set in the path of the actuating member so that a slight movement will cause it to snap closed.

20 In the drawings, Figure 1 is a longitudinal section through the switch as arranged in connection with a time controlled switch actuating mechanism; Fig. 2 is a perspective view of the switch.

25 A is a base of any suitable construction, B and C are the contact members mounted on said base, and D are the blades of the knife switch hinged to the contacts C and adapted to close with the contacts B.

30 E is the insulator cross bar between the blades and F is the actuating handle. Attached to the cross bar E is an outwardly projecting finger G to which is attached a spring H. The other end of this spring is attached to a hook I which is mounted upon 35 the base intermediate the knife blades. The location of the points of attachment is such that when the blades of the switch are open or out of contact with the members B, the spring H will be in the plane of the axis of 40 the hinge, and therefore, will have no tendency to move the blades in either direction.

If however, the blades are moved a slight distance beyond this neutral position the tension of the spring will at once be exerted 45 to snap the switch closed.

As shown in Fig. 1, J indicates a rotatable

arm secured to a clock or other timed mechanism (not shown), and which when actuated will pass through an orbit into which the handle F of the switch projects. Thus 50 the movement of the member J will actuate said handle F sufficiently to throw the spring H over from its neutral position, whereupon the switch will snap closed.

The construction can be applied to any 55 ordinary or standard construction of knife switch and involves but very slight additional expense.

What I claim as my invention is:

1. A switch comprising an insulator base, 60 pairs of contacts mounted thereon, a pair of knife blades hinged to two of said contacts and adapted to bridge with the operating contacts, an insulator cross-bar connecting said knife blades, a projection extending 65 rearwardly from and carried by said cross-bar, a spring attached to the outer end of said projection, and an anchor for said spring secured to said base, said projection being of a length to aline the spring with 70 the axis of the blades when the latter are in slightly open position.

2. A switch comprising an insulator base, 75 pairs of contacts mounted thereon, a pair of knife-edge blades hinged to two of said contacts and adapted to bridge with the operating contacts, an insulator cross-bar connecting said knife-edge blades, a handle secured to said cross-bar, a spring anchored at one end of the base intermediate the knife blades 80 and to the rear of the axis thereof, a handle secured to said cross-bar, and a finger clamped between said handle and cross-bar projecting rearwardly and having the outer end thereof connected to said spring. 85

In testimony whereof I affix my signature in presence of two witnesses.

LLOYD GROFF COPEMAN.
